UNITED STATES PATENT OFFICE.

MANUEL HICKMAN, OF SAN JUAN, TEXAS, ASSIGNOR OF ONE-THIRD TO PERCY M. PERKINS, OF McALLEN, TEXAS.

DUPLEX BALING PRESS.

Application filed March 9, 1925. Serial No. 14,202.

This invention relates to an improved baling press, the same having particular reference to a device of this kind which may be briefly entitled a duplex baling press, owing to the fact that it embodies dual plungers and packers operating in a single housing, to give double capacity and continuous operation.

Briefly, the invention comprises a casing 10 provided with hoppers, into which the material to be packed is introduced, the casing being constructed to provide appropriate receptive compartments for the packed material, and there being opposed plungers 15 mounted for reciprocation in the casing and intermittently and successively operable to force the material into the receptive compartments at the opposite ends of the casing. The invention also embodies power operated 20 means for actuating the plungers, the means embodying packers or tampers for operating in association with the hoppers.

The various advantages and features derived from the construction briefly outlined, 25 will become more readily apparent as the description goes on.

In the accompanying drawing, forming a part of this application, and in which like numerals are employed to designate like parts throughout the same:

Figure 1 represents an approximate central longitudinal section, showing certain parts in elevation, to clearly represent substantially the entire structure.

Figure 2 is an enlarged detail view of the operating means.

Figure 3 is a top plan view of a portion of one of the tampers.

Referring to the drawings in detail, it will 40 be seen that the reference character 1 designates generally an appropriately designed casing, the end portions 2 and 3 of which are adapted to communicate with appropriately constructed receptive compartments 45 (not shown). Suitable hoppers 4 and 5 are located at the opposite ends of the casing, and the top of the casing between the hoppers is provided with an elongated slot 6. Also, the hoppers are formed in their opposed inner walls with slots 7. Mounted for reciprocation in the casing are plungers 8 and 9, the stems 10 of which are slidably mounted on appropriate cross pieces 11 and the heads 12 of which are pivotally con-

nected to the stems as shown. The stems 55 are provided on their upper sides with rack teeth 13. Adapted for cooperation with these teeth are the teeth of gear segments 14 on the inner or lower ends of the levers 15 and 16, both of which are pivotally mounted, 60 as at 17. It will be noted that the lever 16 has its upper portion extending through the slot 6, with its free end portion curved, as at 18, to form a tamping leg 18. The upper portion of the lever 15 is forked, as at 19, 65 and a curved tamper 20 is arranged between the arms of the fork and bolted in place, as indicated at 21. A breakable wooden pin 22 extends through the free ends of the fork arms and the intermediate portions of the tamper 20. A link 23 is pivotally connected to the intermediate portion of the lever 15 and eccentrically connected to the peripheral portion of a toothed wheel 24. Also, a similar link 25 is pivoted to the intermediate 70 portion of the lever 16 and has eccentric pivotal connection with said wheel. The pivotal connection of the adjacent ends of the links is at the same point on the wheel. The wheel is fastened upon a rotatably mounted shaft 26 as shown in Figure 2, and is driven by a pinion 27, receiving motion from a worm wheel 28, cooperating with a rotatable worm shaft 29.

From the foregoing description, it will 85 be evident that I have evolved and produced a novel double acting baling press, the construction being such as to permit material to be placed in the hopper 5, when the tamper 18 is swung clear of the upper end 90 thereof, as shown in Figure 1. While material is thus placed in this hopper, the plunger 9 is compressing material into the portion 2 of the casing. At the same time, the tamper 20, at the other end of the machine 95 is serving to force the material placed in the hopper down in front of the head of the plunger 8. Thus it will be seen that when the tamper at one end is in operation in pressing the material downwardly through the hopper and into the main portion of the casing, the tamper at the other end is swung clear of the hopper, the plunger at the last named end being operated to press the material at the same end into the so-called receptive compartment at this end. Thus it 100 will be seen that alternately operable plungers are provided, which are actuated 105

in succession and a dual arrangement of hoppers and tampers is also provided, the intervals of operation of various parts being properly timed to provide an almost constant or uninterrupted operation of the press.

It is thought that the foregoing description, taken in connection with the accompanying drawings will enable persons skilled in the art to which the invention relates to obtain a clear understanding of the same. Therefore, a more lengthy description is thought unnecessary.

Although the preferred embodiment of the invention has been shown and described, it is to be understood that minor changes coming within the field of invention claimed may be resorted to, if desired.

I claim:

In a baler press, a casing, a hopper upon the casing, a longitudinally slideable plunger 20 mounted in the casing, a lever pivoted intermediate its ends on the casing, a stem extending from the plunger and having rack teeth, a gear segment formed on one end of the lever and meshing with the teeth of said rack, said lever having a curved extension at its other end entering the hopper and forming a tamper, a rotatable member, and a link eccentrically and pivotally engaged with the rotary member and pivotally engaged with the lever between the pivots thereof and the gear segment.

In testimony whereof I affix my signature.
MANUEL HICKMAN.
